UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

DEMOUNTABLE DISPENSER FOR PAPER CUPS.

Application filed March 31, 1923. Serial No. 628,952.

To all whom it may concern:

Be it known that I, CESARE BARBIERI, a subject of the King of Italy, and a resident of the city of New York, in the county of New York and State of New York, have invented certain new and useful Improvements in a Demountable Dispenser for Paper Cups; and I do hereby declare that the following is a full, clear, and exact description of the same, reference being had to the accompanying drawings, and to the numerals of reference marked thereon, which form a part of this specification.

This invention is an improvement on the "paper cup dispenser" shown in my application for patent Serial No. 572,520, filed July 3rd, 1922.

It is an object of this invention to provide a container for paper cups that may be readily removed from its support to permit the cups to be replenished, said container adapted to be readily and securely fastened in position on its support again after such replenishment.

It is a further object of this invention to provide a container for paper cups with a cover that shall keep the cups in place when the container is removed from the support.

Other and further important objects of this invention will be apparent from the disclosures in the drawings and the accompanying specification.

The invention (in a preferred form) is illustrated on the drawings and hereinafter more fully described.

On the drawings:

Figure 1 is a front view of the dispensing container.

Figure 2 is a view in perspective of the supporting plate and the cover slightly separated.

Figure 3 is a side view of the container.

Figure 4 is a vertical central section.

Figure 5 is a bottom plan view.

Figure 6 is a section upon the line 6—6 of Figure 4.

Figure 7 is a section upon the line 7—7 of Figure 6.

As shown on the drawings:

The container is of a general prismatic form in order to fit flat sector-shaped cups. These cups ordinarily have at their small ends, not a point but a short line made by a fold at the bottom of the cups. For this reason the container has in front a narrow

face 10 connected to wider side faces 12 so that the two wider faces do not come to an edge. The narrow face 10 is provided with a vertical slot 13 through which the contents of the container may be seen. If the container is long, it is advantageous to break this slot into several shorter ones by continuing the material of the face 10 all the way across, forming one or more bridges 14. On the interior of the two wide faces 12, near the bottom of the container, are riveted two angle pieces 16 parallel to a pair of slots 18, one in each wide face. The angle pieces 16 are also riveted to a bottom member 20 which serves to support the column of cups. This member is arched downward as is most plainly shown in Figures 4 and 7, and is cut away at the forward edges, as is best shown in Figure 5. The top of the container is formed by continuations of the faces 10 and 12 bent into a horizontal position. Near the top is an oblique partition 22, which is secured in place in any desired manner; for example, a portion of the partition may be bent to a horizontal direction and riveted to the top 21, as shown at 23.

At the rear edge, each side 12 of the container has a flange 24. Each flange is provided with a pair of studs 25, one stud near the upper end and one stud near the lower end. The container is closed by means of a back piece or plate 30, the central portion of which is cylindrical in form, as most clearly shown in Figures 5 and 6. At each side the back surface has a flange 31 adapted to parallel the flanges 24 and contact with the inner faces thereof. The top and bottom of the plate 30 are cut away, as indicated at 32 and 33, for convenience in handling the plate during the assembly of the device. Slots 34 are provided in the plate 30 and the flanges 31, each of which turns upward at its rear end. These slots receive the studs 25 when the cover plate 30 is put in place on the container.

Secured to any convenient support, for example to the wall of a room, is the supporting plate 40. This plate is provided with any convenient means for securing it to the support. The plate 40 has flanges 42 adapted to parallel and be received within the flanges 31. Near each end of each flange 42 is a slot 43, the rear end of which extends downward. The slots are prefer-

ably positioned to cooperate with the studs 25, and so they are adapted to register with the slots 34.

- In the operation of the device, the container is placed with the narrow face 10 downward and the cup-like receptacle thus formed is filled with the paper cups. The partition 22 will cause these paper cups to take the correct oblique position so that they are ready to cooperate with the slots 18 for dispensing. After the cups are in place within the container, the operator takes the plate 30 and puts it in place by passing the slots 34 over the studs 25. The plate 30 is then moved toward the bottom of the container by inserting the fingers between the top 21 and the curved edge 32. This brings the studs 25 into the upturned part of the slots so that the plate is thereby secured in position. The attendant next takes the container, with the cups and the plate 30 in position, to the place where the plate 40 has already been secured to the support and passes the container into position by causing the studs 25 to enter the slots 43, which brings the flanges 42 against the inner faces of the flanges 31, and their edges into contact with the junctions between the curved part of the plate 30 and the flanges 31. The operator then pushes the container downward, which causes the studs 25 to enter the downwardly extending parts of the slots 43 and thus locks the container in position.
- When a person desires to remove a cup from the container, he places his thumb on the thumb piece 15 and the forefinger in the space afforded by the lower cut-away place on the bottom 20, which gives him a firm grip on the lowermost cup, and by pulling it forward, the edges of the cup emerge through the slots 18, so that, although the large end of the cup moves towards the narrow face of the container, the cup is readily removed. When the cup has been drawn out, the column of cups above it descend by gravity. This descent can be watched through the slot 13, and when the supply of cups in the container is nearly exhausted, the attendant will remove the container in order to replenish it. This is done by lifting the container, which causes the studs 25 to come out of the downwardly extending parts of the slots 43. The attendant then pulls the container toward him, which moves the studs 25 to the horizontal part of the slots 43 and releases the container from the supporting plate. The container is then placed in a horizontal position, with the narrow face downward, and the plate 30 is moved toward the top of the container. This is done by pressing with the fingers against the curved edge 33. The curved character of this edge leaves abundant room for the fingers between this plate and the bottom

20. This motion brings the studs into the lower parts of the slots 34 and the plate may then be lifted off from the container, the ends of the studs then passing through the straight part of the slots and then through those portions which are in the curved part 70 30 of the plate. During the motion of lifting the plate off from the container the curved edges 32 and 33 afford space for the fingers. When the plate has been removed, 75 the cups are replenished in the same way that the first supply of cups were placed in the receptacle.

I am aware that numerous details of construction may be varied through a wide 80 range without departing from the principles of this invention, and I therefore do not purpose limiting the patent granted otherwise than necessitated by the prior art.

I claim as my invention:

1. A dispenser for flat cups comprising a removable slotted container shaped to fit the cups, a back plate therefor, a slotted supporting plate, and fastening means for holding the back plate on the container and also 90 serving to hold the container and back plate on the supporting plate.

2. A dispenser for flat sector-shaped cups, including a container comprising two wide side faces and a narrow connecting face, a 95 back plate for said container adapted to be detachably secured between the unconnected edges of said wide side faces, said back plate having curved upper and lower edges whereby space is afforded for the operator's fingers 100 between the back plate and the ends of the container when removing or replacing said back plate.

3. A dispenser for paper cups comprising a container having two wide side faces and 105 a narrow face connecting them at the front, rearwardly extending flanges at the rear edges of said wide side faces, a back plate for said container proper comprising a curved central portion and two side flanges 110 adapted to fit the inner faces of the two flanges of said container, fastening means extending through the container flanges, the flanges of said back plate having slots adapted to cooperate with said fastening means 115 for retaining the back plate in place, and a supporting plate having a flat central portion adapted to be secured to a support and two side flanges adapted to contact the inner faces of the back plate flanges, said supporting plate flanges having slots therein adapted to cooperate with said fastening means for securing the container on said supporting plate.

4. In a dispenser of the class described 125 the combination with a receptacle, of a back plate therefor having a bayonet slot, a supporting plate therefor having a bayonet slot, the closed ends of said bayonet slots being directed in opposite directions, and a stud 130

on said receptacle adapted to cooperate with both of said bayonet slots.

5. A paper cup dispenser comprising a slotted receptacle, a pair of interfitting closure plates having slots therein, and studs mounted on said receptacle adapted to engage in the slots of said closure plates to hold the receptacle and plates connected together.

6. A dispenser for paper cups comprising a receptacle having separated sight slots and a pair of inclined cup outlet slots therein, and a pair of interfitting plates for mounting the receptacle in place and closing the back thereof.

In testimony whereof I have hereunto subscribed my name.

CESARE BARBIERI
